US0D1034189S

(12) **United States Design Patent** (10) **Patent No.:** **US D1,034,189 S**
(45) **Date of Patent:** **** Jul. 9, 2024**

(54) **PACKAGING BOX**

(71) Applicant: **Ursapharm Arzneimittel GmbH**,
Saarbrücken (DE)

(72) Inventor: **Patrick Bittner**, St. Ingbert (DE)

(**) Term: **15 Years**

(21) Appl. No.: **35/515,520**

(22) Filed: **Jul. 14, 2022**

(80) **Hague Agreement Data**

Int. Filing Date: **Jul. 14, 2022**

Int. Reg. No.: **DM/224396**

Int. Reg. Date: **Jul. 14, 2022**

Int. Reg. Pub. Date: **Nov. 4, 2022**

(51) **LOC (14) Cl.** **09-03**

(52) **U.S. Cl.**

USPC **D9/432**

(58) **Field of Classification Search**

USPC D9/414, 415, 420, 423, 432, 433, 721,
D9/600, 601, 627, 628, 629, 643

CPC B65D 65/10; B65D 65/22; B65D 65/24;
B65D 37/00; B65D 53/00; B65D 53/06;
B65D 5/40; B65D 5/42; B65D 5/54;
